UNITED STATES PATENT OFFICE.

JOHN EDWARD OGDEN, OF MOUNTAINVILLE, NEW YORK.

LAG-SCREW EXPANSION-SHIELD.

1,400,405.

Specification of Letters Patent. Patented Dec. 13, 1921.

Application filed September 5, 1919. Serial No. 321,740.

To all whom it may concern:

Be it known that I, JOHN EDWARD OGDEN, a citizen of the United States of America, and a resident of Mountainville, town of 5 Cornwall, Orange county, and State of New York, have invented certain new and useful Improvements in Lag-Screw Expansion-Shields, of which the following is a specification, reference being had to the accompanying drawings, forming a part thereof.

This invention relates to improvements in expansion shields which may be used to secure lag screws and the like in walls of material with which the threads of the screws 15 cannot engage firmly, by being expanded by the insertion of the screws into engagement with surfaces of holes in which the shields are inserted. These shields are longitudinally divided at least throughout the greater 20 part of their length or else are made of two or more longitudinally divided sections which are laterally separated when a screw is forced between them. The specific object of the invention is to decrease the cost of 25 manufacturing by providing a simple structure which may be constructed of stamped metal. Another object is to so form the parts that the expansion occurs in the plane of division instead of at right angles thereto, and 30 to so corrugate the metal as to form screw threads which form a bore which tapers in the plane of division.

These and other objects of the invention will appear in the following specification in 35 which I will describe the invention, the novel features of which will be set forth in appended claims.

Referring to the drawings:

Figure 1 is a sectional elevation of an expansion shield which is made according to 40 and embodies this invention, the section being taken on the line 1—1 of Fig. 2.

Fig. 2 is a bottom plan view of the device shown in Fig. 1.

Fig. 3 is a sectional elevation of another form of expansion shield which also embodies this invention, the section being taken on the line 3—3 of Fig. 4.

Fig. 4 is a bottom plan view of the shield 50 shown in Fig. 3.

Fig. 5 is a sectional elevation of a shield of another modified form of construction, the section being taken on the line 5—5 of Fig. 6.

Fig. 6 is a bottom plan or end view of the 55 form of shield shown in Fig. 5.

Fig. 7 is a sectional elevation taken at right angles to the section of Fig. 5 or on the line 7—7 of Fig. 6.

Fig. 8 is a top plan view of the shield 60 shown in Figs. 5—7.

Like characters of reference designate corresponding parts in all the drawings.

10 designates a tubular shell of stamped or pressed metal of substantially uniform 65 thickness, either divided longitudinally throughout the greater part of its length along lines which are preferably in the same plane, or else constructed of two or more parts and therefore divided longitudinally 70 throughout the length of the device. In either case the dividing lines are those designated by 11 and 12 in Fig. 2. The outermost parts of this shield lie in a common cylindrical imaginary surface.

The walls of this shell are formed into longitudinal corrugations 13 which increase in height slightly from the outer to the inner end of the shell and other corrugations 14 which increase in height to a greater degree. The result is that while the inner part or bore of the shell tapers slightly in the planes of the corrugations 13, it tapers to a greater extent on the plane of the dividing lines 11 and 12 so that the inner end thereof 85 forms an ellipse with its major axis at right angles to the plane of division.

The parts of the shell between the longitudinal corrugations 13, 13 and 14 are helically corrugated as at 15 to form threads 90 with which those of a lag screw or similar device may engage, the threads so formed gradually increasing in height from the outer to the inner end of the shield, those on the corrugations 14 attaining a greater 95 height than those on the other corrugations. At this point it may be remarked that while I have shown the shield as divided on lines 11, 12 passing through the larger corrugations 14, it is to be distinctly understood that such arrangement is not to be taken as a limitation of the invention for the same may be successfully practised by dividing the shell through the corrugations 13. It will now be observed that the corrugations (13, 14), gradually increase in height in planes passing through the axis of the shell and similarly increase in width in planes at right

angles thereto. It may be seen that when this device is inserted in a hole which it approximately fits, and a lag screw is screwed into it, expansion will occur radially along 5 the lines 11 and 12. The metal is comparatively rigid and its stiffness is increased by the corrugations. The result is that the aforesaid expansion causes the shield to be forced into the wall of the hole in which it 10 is inserted and to form a strong and effective anchorage.

A device shown in Figs. 3 and 4 is somewhat similar in construction and operation. It comprises a substantially cylindrical shell 15 20 with its lines of division designated by 21, 22. The longitudinal corrugations in this case extend inwardly from the body proper instead of outwardly as in the former case and are designated respectively by 23 and 20 24, those designated by 24 tapering to a greater extent than the others. The ribs thus formed are also helically corrugated as at 25 to form screw threads.

A still further and perhaps preferred 25 form of construction is shown in the remaining figures of the drawings. In these figures the shell is designated by 30 divided on the plane of lines 31, 32. Near its outer end are some outwardly extending longitudinal corrugations 33, beyond which is an annular 30 groove 34 for the reception of a ring 35 of spring wire which serves to hold the parts of the shell together. The rest of the body of the shell is corrugated helically to form 35 screw threads which in the plane of the line 7—7, (Fig. 6), or in other words along the major axis of the ellipse, are of uniform height as shown in Fig. 7, but which in the plane of the lines of division 31 and 32 progressively increase in height toward the inner 40 end of the shield as shown in Fig. 5. The shield is further strengthened and stiffened by having the edges adjacent the lines of separation turned outwardly to form longitudinal ribs 36. In either case the screw threads themselves may be of uniform height throughout the length of threaded part of the device, so long as the shield is so formed that the maximum taper of the threaded 45 50 bore is in the plane of the line of division.

I have illustrated and described a number of forms of construction of expansion shields which embody this invention in order to show that I do not intend to limit myself to any particular form of construction and in fact I intend no limitations other than those imposed by the appended claims.

What I claim is:

1. An expansion shield comprising a tubular body forming expansion members divided from each other at least a part of the length of the body, the walls of said body being corrugated to form screw threads, the outside of which corrugations lie substantially in a cylindrical surface, said corrugations progressively increasing in height in a given axial plane toward the inner end of the body to a greater extent than in similar planes angularly adjacent said given plane.

2. An expansion shield comprising a tubular body forming expansion members divided from each other in one plane at least a part of the length of the body, the walls of said body being corrugated to form screw threads, the outside of which corrugations lie substantially in a cylindrical surface, said corrugations progressively increasing in height in the plane of division toward the inner end of the body to a greater extent than in planes removed from said plane.

3. An expansion shield comprising a tubular body forming expansion members divided from each other at least a part of the length of the body, the walls of said body being corrugated, the outside of which corrugations lie substantially in a cylindrical surface, said corrugations progressively increasing in height in the planes of division toward the inner end of the body to a greater extent than in other planes.

4. An expansion shield comprising a tubular body forming expansion members divided from each other at least a part of the length of the body, the walls of said body being corrugated to form screw threads, the outer parts of said body lying substantially in a cylindrical surface and said corrugations forming a threaded bore which tapers in the plane or planes of the lines of division to a greater extent than in other planes.

5. An expansion shield comprising a tubular body forming expansion members divided from each other at least a part of the length of the body, the walls of said body being provided with a plurality of corrugations the outside of which lie substantially in a cylindrical surface, the corrugations in the plane of division increasing in height toward the inner end of the body, and the corrugations away from the plane of division increasing in a similar manner but to a lesser degree.

6. An expansion shield comprising a tubular body forming expansion members divided from each other in one plane at least a part of the length of the body, said body having near one of its ends longitudinal corrugations forming outwardly projecting ribs, and being helically corrugated throughout another portion of its length to form screw threads progressively increasing in height in the plane of division of the members to a greater extent than in other planes, and the outside of said helical corrugations lying substantially in a cylindrical surface.

7. An expansion shield comprising similar members divided from each other in one

plane, said shield having near one of its ends longitudinal corrugations forming outwardly projecting ribs and an annular groove, and being helically corrugated throughout another portion of its length to form screw threads progressively increasing in height in the plane of division of the members to a greater extent than in other planes, the outside of said helical corrugations lying substantially in a cylindrical surface, and a holding means in the annular groove.

8. An expansion shield comprising a tubular body divided longitudinally for at least a portion of the length of the same to provide two or more expansion members and provided with longitudinal corrugations in the plane of such division, said body being further corrugated to form screw threads gradually increasing in height in said plane of division.

9. An expansion shield comprising a tubular body divided for at least a portion of its length to form a plurality of expansion members, and provided with longitudinally extending ribs helically corrugated into screw threads increasing in height longitudinally of the shield.

10. An expansion shield comprising a tubular body divided for at least a portion of its length to form a plurality of expansion

members, and provided with longitudinally extending ribs helically corrugated into screw threads increasing in height longitudinally of the shield, the helical corrugations in the ribs nearest the lines of division increasing in height to a greater extent than the others.

11. An expansion shield comprising a tubular body divided for at least a portion of its length into a plurality of expansion members and provided with longitudinally extending corrugations forming a plurality of ridges which lie in the surfaces of a plurality of imaginary cones of relatively different angularity.

12. An expansion shield comprising a tubular body, the walls of which are corrugated to form screw threads with the outside of the corrugations lying substantially in a cylindrical surface, said corrugations progressively increasing in height in a given axial plane from one end toward the opposite end of the body and said body further having longitudinal corrugations intercepting the screw thread corrugations aforesaid.

In witness whereof I hereunto set my hand this 21st day of August, 1919.

JOHN EDWARD OGDEN.

Witness:

I. B. MOORE.
